(57) **CLAIM**

The ornamental design for a removable hard top for a motor vehicle, as shown and described.

DESCRIPTION

FIG. 1 is a top side perspective view of a removable hard top for a motor vehicle showing my new design, wherein the motor vehicle is shown in broken lines and forms no part of the claimed design;

FIG. 2 is a top front perspective view of the removable hard top for a motor vehicle;

FIG. 3 is a top rear perspective view thereof;

FIG. 4 is a top left side perspective view thereof;

FIG. 5 is a front perspective view thereof;

FIG. 6 is a rear perspective view thereof;

FIG. 7 is a left side elevational view thereof, the right side elevational view being identical thereto;

FIG. 8 is a top plan view thereof;

FIG. 9 is a bottom plan view thereof;

FIG. 10 is a front elevational view thereof; and,

FIG. 11 is a rear elevational view thereof.

The broken lines shown in FIGS. 1, 9 and 11 are for illustrative purposes and form no part of the claimed design.
